UNITED STATES PATENT OFFICE.

HENRY M. LASHER, OF KANSAS CITY, KANSAS, ASSIGNOR TO THE KANSAS CITY GASOLINE COMPANY, OF KANSAS CITY, KANSAS, A CORPORATION OF KANSAS.

STILL.

Application filed July 1, 1920. Serial No. 393,424.

My invention relates to the art of refining oil, and has for its object the production of an apparatus which will more efficiently perform the necessary functions described in my prior copending application Serial No. 376,103, filed April 23, 1920. In said application, I disclosed a shelf to hold a catalyzer such as coal or carboniferous material. In the present case I present a complete still structure or organization with the shelf suspended adjustably from above so that it is out of contact with the walls of the still, and can be adjusted by the operator during a run. This is the result of my discovery that the distance at which the carbonaceous material is held from the bottom of the still has a marked effect upon the results obtained and that the critical distance at which the most desirable results are obtained is not always the same, varying for different kinds of oil, differences in gravity, and according to circumstances incident to the process itself. To meet these variable conditions I make the shelf adjustable at the will of the operator without opening the retort, during operation. Among the advantages gained by this form of construction are, that the weight of the shelf and catalyzer are supported separately from the still body, thereby relieving the latter of considerable strain, which is important if any vacuum forms in the still tending to collapse it; also by permitting the shelf to be raised in cleaning, to give room for men to work in an upright position.

In the accompanying drawings illustrating the invention:

Fig. 1 is a longitudinal vertical section of the still;

Fig. 2 is a vertical transverse section; Fig. 3 is a horizontal longitudinal section, showing part of the shelves or screens in position;

Figs. 4, 5, 6 and 7 are details of the suspension means.

In the drawings, 1 is the body of the still, 2 is the shelf suspended therein comprising a rack having longitudinal members 4 and cross members 5 supported from vertical suspension devices 3 comprising rod and chain construction shown in detail in Figs. 4, 5, 6 and 7. On the shelf 2 is a series of screens 6 extending from end to end of the shelf and of such dimensions as to be possible of withdrawal and insertion through the usual manhole.

In operation the catalyzer 6 employed as described in the aforesaid applications is placed upon the screens 6, and hangs immersed in the oil at a depth determined by the operator by means of the hand-wheels 8. Beneath the screens is suspended a pan 7 to catch falling particles which would otherwise clog and burn onto the walls of the still.

What I claim is:

The combination of a still for cracking hydrocarbons and a rack, means for suspending said rack within the still and means for adjusting the vertical position of said rack, said adjusting means being operable from without the still, and stuffing boxes through which said suspending means pass.

In testimony whereof I hereunto affix my signature.

HENRY M. LASHER.
